US00D516836S

(12) United States Design Patent (10) Patent No.: US D516,836 S
(45) Date of Patent: * Mar. 14, 2006

(54) SHELF UNIT

(75) Inventors: Jeffrey B. Katz, Hickory, NC (US);
Gary A. Huffstetler, Lenoir, NC (US);
Scott C. Dergins, Morganton, NC (US)

(73) Assignee: Broyhill Furniture Industries, Inc.,
Lenoir, NC (US)

() Term: 14 Years

(21) Appl. No.: 29/202,818

(22) Filed: Apr. 5, 2004

(51) LOC (8) Cl. 06-04

(52) U.S. Cl. D6/474

(58) Field of Classification Search D6/436-439,
D6/477-479, 474; 312/196, 204, 224, 279

See application file for complete search history.

(57) CLAIM

The ornamental design for a shelf unit, as shown and described.

DESCRIPTION

FIG. 1 is a perspective view of a shelf unit showing our new design;

FIG. 2 is a front elevational view thereof;

FIG. 3 is a right side elevational view thereof, the left side being a mirror image of the right side; and,

FIG. 4 is a top plan view thereof.

The surfaces or portions of the article not shown in the Figures or described in the specification form no part of the claimed design.

1 Claim, 4 Drawing Sheets
